COMBINED OPTICAL AND NASAL AIR FILTER MASK

Robert A. Stegman, 2151 NE. 124th St.,
Miami, Fla. 33161

Filed May 14, 1973, Ser. No. 359,660

Term of patent 14 years

Int. Cl. D24—99; D2—03

U.S. Cl. D83—1 K

FIG. 1 is a front elevation of a combined optical and nasal air filter mask, showing my new design;

FIG. 2 is a top plan view thereof;

FIG. 3 is a left side elevation thereof;

FIG. 4 is a rear elevation thereof; and

FIG. 5 is a bottom elevation thereof.

The right side elevation of the mask is the same as shown in FIG. 3.

I claim:

The ornamental design for a combined optical and nasal air filter mask, as shown and described.
